Attorney

UNITED STATES PATENT OFFICE.

ALBERT G. REDMOND, OF INDIANAPOLIS, INDIANA, ASSIGNOR TO THE MARVEL CAR-BURETER COMPANY, OF FLINT, MICHIGAN, A CORPORATION OF INDIANA.

AIR HEATER FOR CHARGE-FORMING DEVICES.

Application filed December 15, 1919. Serial No. 344,931.

This invention relates to an air heater for charge forming device used in connection with internal combustion engines, the object being to provide a heating device which is 5 arranged at the air inlet of the charge forming device whereby the air before it enters the charge forming device will be quickly heated so as to allow the charge forming device to form a perfect combustible mixture.

Another and further object of my invention is to provide a heater which is so connected to the exhaust pipe of the internal combustion engine that the exhaust gases can 15 be diverted from their natural path of travel through the heating device whereby the air entering the carburetor will be quickly heated in order to allow the engine to be quickly warmed up without the additional use of 20 fuel.

A still further object of the invention is to provide a heater having a plurality of radiating fins forming a plurality of air passages through which the air passes in its 25 passage to the charge forming device in order to enable the air to be quickly heated in starting the motor to which the charge forming device is attached.

A still further object of the invention is to 30 provide an air heater for a charge forming device for an internal combustion engine which is under the control of the operator whereby the exhaust gases can be diverted from the natural path of travel, to the heating device or allowed to travel in their usual 35 course to the muffler.

Other and further objects and advantages 40 of the invention will be hereinafter set forth and the novel features thereof defined by the appended claims.

In the drawings:

Figure 1 is a side elevation of an internal combustion engine showing the application 45 of my improved construction of air heater for the charge forming device.

Figure 2 is an enlarged longitudinal section through the heater; and

Figure 3 is an end view of the heater.

In the drawing 1 indicates an internal 50 combustion engine provided with the usual intake manifold 2 to which is connected the charge forming device 3 which is provided with an air inlet 4. The internal combustion engine is provided with an exhaust manifold 5. The above description is given so that

the operation of my improved construction of air heater for charge forming devices can be readily understood.

Connected to the exhaust manifold 5 is an exhaust pipe 6 which in turn is connected to the coupling member 7 from the opposite end of which extends the exhaust pipe 8 leading to the muffler in the ordinary manner. Coupling member 7 is provided with threaded apertures 9 and 10 in which are secured pipes 11 and 12 and while I have shown rigid pipes mounted in these apertures it is of course understood that flexible tubes can be used and I do not wish to limit myself to the use of any particular kind of tube or manner of securing the same within the apertures 9 and 10. The coupling member 7 has a valve stem 13 extending transversely therethrough carrying a valve 14 for closing the passage whereby the exhaust gases from the internal combustion engine will be discharged through the aperture 9 into the tube 11. The valve stem 13 carries an arm 15 to which is connected a rod 16 extending through the dash 17 of the motor vehicle in which the internal combustion engine is installed, said rod having a knob 18 for operating the same and it will be seen that by this construction when the rod is in the position shown in full lines in Figure 1 the valve 85 will be in closed position as shown in dotted lines in Figure 2 so as to close the passage in the coupling member 7.

The ends of the pipes 11 and 12 extend into suitable openings 19 and 20 formed in a casting 21 which is preferably tubular in shape having a closed end 22 and provided with longitudinally disposed partition 23 which terminates short of the closed end 22 in order to cause the exhaust gases entering 90 the opening 19 to pass around the end of the partition and out of the opening 20.

The outer face of the tubular casting forming the heater proper is provided with longitudinally disposed fins or ribs 24 over 100 which is arranged a shell 25 which is provided with a coupling portion 26 adapted to be connected to the air intake 4 of the charge forming device. The shell 25 terminates short of the enlarged portion of the casting 21 in order to allow air to pass into the air passageways formed by the fins and shell. It will be seen by this construction a plurality of air passages are formed by the fins and shell whereby the air in its passage through 105 110

these passageways will be quickly and thoroughly heated before it enters the air intake of the charge forming device which is herein shown as a carburetor of the Marvel type but it is of course understood that the heater is capable of being used in connection with any construction of charge forming device now in use.

In the operation of the heater as herein shown assuming that the valve in coupling member 7 of the exhaust line pipe is in closed position when it is desired to start the internal combustion engine the rod 16 is pulled out by the operator grasping the knob 18 into the position shown in Figure 1 which moves the valve into closed position as shown in dotted lines in Figure 2 and as the exhaust gases are expelled through the exhaust manifold they pass down through the aperture 9 through the pipe 11 into the heater which is located at the air inlet of the charge forming device. The exhaust gases entering the heater are caused to travel longitudinally of the heater towards the closed end around the end of the partition and then back and are conveyed by the pipe 12 into the coupling member 7 to the other side of the valve 14 and are carried to the muffler in the ordinary manner. As the entire volume of exhaust gases is carried through the heater which is formed of a metal casting with a plurality of fins the same quickly becomes heated and as the air is caused to enter the charge forming device through a plurality of air passages separated by radiating fins the air is quickly heated so that the air admitted to the charge forming device quickly heats the same in order to allow a perfect combustible mixture to be produced.

From the foregoing description it will be seen that I have provided an air heater for a charge forming device which is located at the air inlet of the charge forming device

and it is provided with means for diverting the exhaust gases from the exhaust line pipe through the same so as to quickly heat the air in its passage to the charge forming device and while I have shown certain details of construction I do not wish to limit myself to the particular construction of heater and manner of connecting the same as shown as my invention consists in broadly locating a heater at the air inlet of a charge forming device and means provided for conveying the exhaust gases directly to said heater so as to allow the heater to become hot quickly in order to produce a high explosive charge without the additional use of extra fuel as now employed when warming up an internal combustion engine.

What I claim is:—

The combination with an internal combustion engine having an intake manifold and exhaust manifold, of a charge forming device connected to the intake manifold and having an air inlet, a casting arranged at the outlet of said exhaust manifold having a valve for controlling the passage of exhaust gases therethrough, said casting having outlet and inlet apertures, a tubular shaped member having a closed end and provided with a longitudinally disposed partition terminating short of its closed end and connected to said apertures of said casting by pipes forming a passageway for the exhaust gases when said valve is in closed position, said tubular member being provided with longitudinally disposed fins and a shell of a larger diameter than said tubular member arranged over said tubular member upon said fins, said shell being connected to the air inlet of said carburetor.

In testimony whereof I have hereunto affixed my signature.

ALBERT G. REDMOND.
